UNITED STATES PATENT OFFICE.

CLIFFORD B. CRONAN, OF SHELBURNE FALLS, MASSACHUSETTS.

PENCIL SHARPENER.

Application filed November 9, 1922, Serial No. 599,393. Renewed April 17, 1926.

My invention relates to pencil sharpeners and more particularly to mechanically operated pencil sharpeners employing a rotary cutter for sharpening and pointing pencils.

5 One object of my invention is to provide an improved cutter device which shall be adapted to generate a pencil point having a desired contour and this object is accomplished by causing the cutter to move in a predetermined manner to produce the desired contour of pencil point.

Another object of my invention is to provide an improved chuck mechanism for supporting and automatically shifting the position of a pencil relative to the cutter during the sharpening operation, so that any desired length of point may be produced on the pencil.

Other objects of the invention will be apparent from the novel construction and arrangement of parts, as shown in the following specification and as specifically set forth in the appended claims.

The invention is illustrated in the accompanying drawings, in which

Figure 1 is a front elevation of my improved pencil sharpener;

Fig. 2 is a side elevation of the same;

Fig. 3 is a transverse section on the line 30 3—3 of Fig. 1;

Fig. 4 is a rear elevation;

Fig. 5 is a plan view with the casing in horizontal section;

Fig. 6 is a detail front elevation with the chuck removed and the chuck casing in section;

Fig. 7 is a longitudinal section of the chuck, and

Fig. 8 is a diagram illustrating the principles upon which the device operates.

In carrying out my invention, I employ a pedestal 1 which may be of any convenient form and may be secured in an upright position upon a table, as shown in Figs. 1, 2, 3 and 4, or may be secured to a side wall or other fixed support, as indicated by the dotted lines in Fig. 4. Upon the said pedestal, I mount a casing consisting of mating members 2 and 3 which are fastened together by stud screws or bolts 4 which may be placed at convenient intervals. This casing is secured to the pedestal by a stud bolt 5 inserted transversely through the upper end of the pedestal so that the casing may be supported in an upright position whether the pedestal be secured upon a table or upon

a wall. The casing is of a general circular form and its top portion consists of a transparent member 6 which may be of celluloid or other material carried in a substantially semi-circular frame 7 which is secured to the casing members 2 and 3 by suitable screws 8, as will be readily understood. The space between the lower portions of the casing members 2 and 3 is left open, as shown clearly in Fig. 3, to permit discharge of the chips and particles of lead, and in the outer surfaces of the casing members I form grooves 9 in which are slidably engaged the lips or flanges 10 at the upper edges of a chip receptacle 11 which may be of any convenient form and is equipped with a transparent member 12 in one side so that the user may be informed as to when the receptacle is full and should be emptied.

Upon the outer side of the casing member 3 is formed or secured a boss or cylindrical chamber 13, and a spindle 14 is rotatably fitted in the outer end wall of this boss or chamber and in the casing member 2, the spindle being formed with an annular shoulder 15 and being equipped with a stop collar 16 at opposite sides of the wall of the front casing member 2 whereby endwise movement of the spindle is prevented. Upon the rear end of the spindle is secured a crank 17 or other convenient form of handle whereby the spindle may be easily rotated, as will be readily understood. Upon the spindle is fitted a drum 18 having a cam 90 groove 19 in its outer circumferential surface and provided in its bore with a longitudinal groove 20 which is engaged by a stud or pin 21 on the spindle whereby the rotation of the spindle is imparted to the drum and the drum is permitted endwise movement along the spindle. The cutter or knife 22 is secured to the front end of the drum in any convenient manner and, of course, partakes of the motion of the drum, being rotated with the spindle 14 and also moving along the same rearwardly as a cut is made and then returning to its initial position during the succeeding portion of the rotation.

Through the front casing member 2 is formed an opening 23 to admit the end of a pencil 24, and upon the outer side of the said casing member is formed a chuck casing 25 which supports a chuck 27 for resiliently gripping the pencil and holding the same in an oblique position relative to the

cutter blade. This chuck is illustrated as a cylindrical tube in which is secured a sleeve member 28 provided with resilient inner portions 29 contracted so as to be spaced from the wall of the tube 27 in order to provide a greater range of gripping action on the pencil. The sleeve is shown as composed of resilient members arranged to extend longitudinally of the pencil, but it is obvious that the sleeves 28 may be provided with spiral members adapted to encircle and grip the pencil. Whichever form of sleeve is employed, it may be desirable to aid the gripping action on the pencil supported therein by means of a spring 30 coiled around the resilient members associated therewith, as shown in Fig. 7. The inner end of the split spring sleeve is flared as indicated by the numeral 31, thereby providing retaining means for the spring 30. Fixed upon the outer circumference of the chuck is a helical gear 32 which meshes with a helical gear or worm 33 mounted in any convenient manner so as to rotate the chuck tube 27, as will be readily understood. As shown most clearly in Fig. 5, the gear 32 abuts the outer end of the chuck casing which provides a thrust bearing for said gear and the chuck in one direction. The chuck cover and gear casing 26 is secured upon the casing and is properly formed to fit around the end of the chuck and of the chuck casing and enclose the gearing by which the chuck is rotated. It will be readily noted that the chuck cover and gear casing is constructed with an internal annular shoulder which forms a thrust bearing at the outer side of the gear 32, so that end-wise movement of the chuck is prevented. The helical gear 33 is formed integral with or fixed rigidly to a concentric Geneva stop wheel 34 which is adapted to be periodically engaged and actuated by a pin 35 carried by the stop collar 16 which is secured upon the front end of the spindle 14. The cam groove 19 is engaged by a roller 36 mounted upon the inner end of a stud 37 which is screwed through one wall of the offset or chamber 13, as shown. It will thus be readily seen that, as the spindle 14 is rotated, the cutter is caused to also rotate about the said spindle as a center and through the engagement of the cam groove 19 with the roller 36, the drum and the cutter are caused to move rearwardly along the spindle. By rotating the cutter the stop collar 16 is also rotated and, through a portion of the rotation, the pin 35 on said stop collar engages and actuates the Geneva stop wheel 34 and a partial rotation is thereby imparted to the gears 33 and 32 so that the chuck is rotated one step and the pencil likewise rotated about its own axis to present a fresh surface to the cutter. It will, of course, be understood that the cutter operates upon the pencil during

a portion of its revolution, and during the remaining portion of its revolution is returning to its initial position, and the pencil is rotated during the return movement of the cutter.

Within the casing, a stop or rest 38 is secured upon the front wall of the same and in alignment with the chuck 27 and the opening 23 in the casing so that the end of the pencil may be resiliently supported against the thrust of the cutter and the insertion of the pencil may be properly limited. This stop may conveniently be a resilient sheet metal bracket having a cup-like member 39 presented to the opening 23 and having a conical portion 40 extending axially from the cup-like portion. When a new pencil is to be sharpened, it is inserted through the chuck so that its end bears against and rests in the cup-like portion 39 of the stop rest. The cutter is then operated so as to cut completely around the pencil and a blunt point will be thereby formed. If it be then desired to produce a long tapering point of lead, the pencil is further inserted so that the extreme point thereof will rest in the conical grooved portion 40 of the rest, and the sharpening operation is repeated.

As shown and as will be readily understood, the chuck is disposed obliquely to the cutter so that the pencil to be sharpened extends across the plane of the cutter, and in Fig. 8 I have illustrated diagrammatically the mathematical considerations upon which the successful operation of the invention is based. A cutting edge of symmetrical mathematical form is rotated about an axis so as to cut a chip from the end of the pencil. The desired cutting results may be obtained either by giving the cutter a combined rotary and axial movement or by providing a spacially formed or warped cutter adapted to combine both the radial and axial components necessary to generate the same contour when rotated about the proper axis.

The form of cutter which I have chosen for illustration is a semi-circular cutter having a center O' mounted to rotate about an eccentric axis O. This form of blade is an easy one to produce and grind and possesses satisfactory cutting properties. The plan shows the axis of the pencil inclined at an angle A to the plane of the cutter blade and also at a certain distance above the axis of the rotation of the cutter (see elevation). This angle is adjusted in relation to the angle of taper of the pencil point to give satisfactory clearance to the cutting edge and have a smooth operation. In the elevation, one hundred and eighty degrees of rotation are spaced off every ten degrees, and the radial lines, projecting from the center of rotation, for these equal angles intersect the periphery of the cutter blade and divide

it into arcs of varying length. The first angle of thirty degrees gives the necessary clearance for the cutter before it comes in contact with the wood of the pencil and 5 starts to cut. As the cutter continues through successive equal angles of rotation, each arc of the cutting edge passes through the plane of the pencil at a constantly increasing distance in radial direction from 10 the center of rotation. In cutting, the advance of the cutter in the plane of the pencil and in the direction of the pencil point is gradually increased to a maximum and then gradually decreased to a minimum as the 15 end of the pencil is reached. It may thus be stated that the angle of cut caused by the radial and axial advance of the cutting edge along the pencil varies gradually and the consecutive arcs are practically parallel. 20 through the largest portion of its radius of action, thus insuring a smooth cutting action. By thus producing different proportions of varying radial and axial advance of the cutter during each revolution thereof, 25 the cutter may be caused to move so as to produce any desired symmetrical point on the pencil. The plan in the diagram shows how each unit of radial advance of the cutter must be combined with the proper 30 amount of axial advance to generate any predetermined contour for the pencil point, this motion being synchronized by the action of the cam drum.

Normally, the cutter produces a point of 35 circular cross section, the pencil being automatically shifted about its own axis through the action of the Geneva stop wheel and the parts associated therewith, as hereinbefore set forth. If it be desired to produce a 40 chisel point, the pencil is inserted in the usual manner and one complete cut is made. The pencil is then withdrawn and manually rotated about its own axis through an angle of one hundred and eighty degrees 45 and then re-inserted in the chuck and the cutter operated to make another complete cut. This process obviously acts upon diametrically opposite portions of the pencil so that a chisel-like point of lead is produced.

When a new pencil is to be sharpened, it is inserted through the chuck in the usual manner and its end will abut the cup-like portion 39 of the stop rest. The cutter is 55 then operated in the usual manner, and as a result of the operation will reduce the end of the pencil so as to form a blunt point. This operation may be all that is needed to 60 sharpen crayons or similar marking elements. If, however, it be desired to produce a sharp lead point, the pencil is pushed further through the chuck after the blunt point has been formed, so that its reduced 65 extremity rests in the tapered conical portion of the stop rest, and further operation

of the cutter then produces the desired point upon the lead. It will be readily noted that the pencil is firmly supported in the chuck so that it will properly resist the thrust imposed by the action of the cutter but at the 70 same time there is sufficient yielding to prevent breaking of the lead or excessive strain upon the cutter. It will be readily noted that the shaving action of the cutter is in the direction of the grain of the wood of the 75 pencil and not across the grain, thereby producing a smooth surface and having the least tendency to break the lead. The reduction of the tendency to cause breakage is aided by the peculiar shearing cut taken, 80 the ratio of the length of cutting edge coming into contact with the work to the amount of advance in the direction of the point being adjusted to secure free cutting action. It will be noted that the cutter starts to 85 remove a chip as it rotates about its axis and comes into contact with the outside of the pencil, the chip being removed from heel to point by the continued rotation of the cutter combined with an axial motion. My 90 improved pencil sharpener is simple, compact, easily operated, may be produced at a low cost and will be found uniformly efficient in use.

Having thus described the invention, what 95 is claimed as new is:

1. A pencil sharpener including a cutter having a symmetrical cutting edge and mounted for eccentric rotation, means for rotating the cutter and for moving it along 100 the axis of its rotation, and means for supporting a pencil across the path of travel of the cutter and obliquely to the same.

2. A pencil sharpener including a cutter having a semi-circular cutting edge, means 105 for rotating the cutter about an eccentric axis, means for effecting movement of the cutter along its axis of rotation during its rotary movement, and means for supporting a pencil obliquely across the plane of the 110 cutter.

3. A pencil sharpener including a cutter having a symmetrical cutting edge and mounted for rotation about an axis eccentric to said edge, a drum to which the cutter is secured and disposed concentric with the axis of rotation of the same, said drum having a longitudinal groove extending through its bore, means for effecting endwise movement of the drum, a spindle extending through the bore of the drum, a fixed member on the spindle engaging the groove in the drum, means for rotating the spindle, and means for supporting a pencil obliquely across the 115 plane of the cutter.

4. A pencil sharpener including a tubular chuck to receive and hold a pencil, a stop rest spaced from and aligned axially with the chuck, a cutter disposed in a plane at an oblique angle to the axis of the chuck and 120

125

130

- intersecting said axis between the chuck and the stop rest, and means for simultaneously rotating the cutter and positively moving the same along its axis of rotation.
5. 5. A pencil sharpener including a tubular chuck, a stop rest spaced from and aligned axially with the chuck and having a cupped portion presented to the chuck and a tapered conical portion extending axially from the cupped portion, a cutter disposed in a plane at an oblique angle to the axis of the chuck and the said stop rest, and means for rotating said cutter and moving it along its axis of rotation.
15. 6. A pencil sharpener including a chuck consisting of a tube, a longitudinally split spring sleeve secured at one end in the outer end of the tube and adapted to fit closely around a pencil inserted through the tube, the ends of the tube being flared, a spring coiled around said sleeve between the same and the tube and having its ends bearing against the flared ends of the sleeve, a cutter disposed at an oblique angle to the axis of the chuck, and means for simultaneously rotating the cutter and moving it bodily along its axis of rotation.
25. 7. A pencil sharpener including a chuck constructed to receive and support a pencil to be sharpened, a cutter mounted at an oblique angle to the axis of the chuck, means for rotating the cutter and simultaneously moving it endwise along its axis of rotation from and toward the pencil, and means for partially rotating the chuck and the pencil therein during the endwise movement of the cutter toward the pencil.
35. 8. A pencil sharpener including a spindle, a cutter mounted on the spindle to rotate therewith and move bodily along the same during its rotation, a chuck disposed at an oblique angle to the plane of the cutter, a Geneva stop wheel disposed adjacent the chuck, gearing operatively connecting the chuck with said stop wheel, and gearing operatively connecting the Geneva stop wheel with the spindle whereby the chuck will have alternate intervals of rest and movement during rotation of the spindle.
45. 9. A pencil sharpener comprising means for holding a pencil to be sharpened, a rotary cutter arranged to cut the pencil obliquely to its axis and move longitudinally thereof, and means for varying the angle of cut during the longitudinal movement of the cutter along the axis of said pencil.
55. 10. A pencil sharpener comprising means for holding a pencil to be sharpened, a rotary cutter arranged to cut the pencil obliquely to its axis and move longitudinally thereof, and means for progressively diminishing the angle of cut during the longitudinal movement of the cutter along the axis of said pencil.
60. 11. A pencil sharpener comprising a chuck for holding a pencil to be sharpened, an arcuate cutter blade mounted for eccentric rotation, means for rotating the cutter and advancing the cutter edge obliquely to the axis of the pencil, whereby the angle of the cut caused by the cutter edge varies from a maximum to a minimum during each rotation of the cutter.
65. 12. A pencil sharpener comprising means for holding a pencil to be sharpened, a rotary cutter blade, and means for rotating the cutter and simultaneously moving said cutter along its axis of rotation, whereby the angle of the cut caused by the cutter, varies from a maximum to a minimum during each rotation of the cutter.
70. 13. The method of sharpening a pencil, which comprises advancing a cutter obliquely to the axis of the pencil and longitudinally thereof, and progressively diminishing the angle of cut during the longitudinal advancement of the cutter to the axis of the pencil.
75. 14. The method of sharpening a pencil, which comprises advancing a cutter obliquely to the axis of the pencil and longitudinally thereof and varying the angle of cut during the longitudinal advancement of the cutter to the axis of the pencil.
80. 15. A pencil sharpener comprising a drum having a cam groove in its circumferential surface, a fixed stud engaging said cam groove, means for rotating the drum and permitting endwise movement of the same during its rotation, a cutter secured to the forward end of the drum and mounted eccentric to the axis thereof, and means for supporting a pencil obliquely across the plane of the cutter.

In testimony whereof I affix my signature.
CLIFFORD B. CRONAN. [L.S.]
